UNITED STATES PATENT OFFICE

137,272

DESIGN FOR A DOLL

Florence Fannie Fullerton, Astoria,
Long Island, N. Y.

Application July 23, 1943, Serial No. 110,737

Term of patent 3½ years

To all whom it may concern:

Be it known that I, Florence F. Fullerton, a citizen of the United States, residing at 30-12 35th Street, Astoria, L. I., in the county of Queens and State of New York, have invented a new, original, and ornamental Design for a Doll, of which the following is a specification, reference being had to the accompanying drawings, forming part thereof.

In the drawings:

I claim:

The ornamental design for a doll, as shown.

FLORENCE FANNIE FULLERTON.
